United States Patent Office

Des. 221,908

Patented Sept. 14, 1971

221,908

SURGICAL INSTRUMENT HOLDER

Howard Berkowitz, Stony Brook, N.Y., assignor to Surgi-Med Corporation, Great Neck, N.Y.

Filed Jan. 12, 1970, Ser. No. 20,875

Term of patent 14 years

Int. Cl. D24—99; D5—03

U.S. Cl. D83—1

FIG. 1 is a prospective view of the surgical instrument pad showing my new design.

FIG. 2 is an enlarged prospective view of one of the projections on the surgical instrument pad.

FIG. 3 is a top plan view of the projection shown in FIG. 2.

FIG. 4 is a bottom plan view of the projection shown in FIG. 2.

FIG. 5 is a side elevational view of the projection shown in FIG. 2.

FIG. 6 is a sectional view taken on line 5—5 of FIG. 5.

The side opposite that shown is the same as the side that is shown.

I claim:

The ornamental design for a surgical instrument holder, substantially as shown and described.
